(57) **CLAIM**

The ornamental design for an absorbent article substrate with a pattern, as shown and described.

DESCRIPTION

FIG. 1 is a front view of an absorbent article substrate with a pattern;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The claimed design comprises an ornamental surface pattern printed on flat surfaces in a single plane.

The broken lines within the solid-line boundaries of the claimed design, having the appearance of stitching, form a part of the claimed design. All other broken lines shown in FIGS. 1-6 illustrate portions of the absorbent article substrate with a pattern that form no part of the claimed design. The surfaces or portions not shown in the drawings or described in the specification form no part of the claimed design.
